UNITED STATES PATENT OFFICE.

ULYSSES S. ARMSTRONG, OF NEW KENSINGTON, PENNSYLVANIA.

COATING OF METAL ARTICLES.

1,012,047.

Specification of Letters Patent.

Patented Dec. 19, 1911.

Application filed November 1, 1910. Serial No. 590,187.

To all whom it may concern:

Be it known that I, ULYSSES S. ARMSTRONG, a resident of New Kensington, in the county of Westmoreland and State of Pennsylvania, have invented a new and useful Improvement in Coating of Metal Articles; and I do hereby declare the following to be a full, clear, and exact description thereof.

My invention relates to the coating of metal articles, and has special reference to the coating of the interior and exterior surfaces of pipes or tubes.

The object of my invention is to provide a cheap, simple and efficient apparatus for the coating of metal articles, such as pipes or tubes, which will enable such articles to be coated on their inner and outer surfaces in a rapid and easy manner with a metallic coating, such as lead and tin, or zinc, as well as enabling such a coating to be formed on such articles evenly and uniformly and without any waste of the material composing such coating.

To these ends my invention consists, generally stated, in the novel arrangement, construction and combination of parts employed in my improved coating of metal articles, as hereinafter more specifically set forth and described and particularly pointed out in the claims.

To enable others skilled in the art to which my invention appertains to construct and use the apparatus employed in my improved coating of metal articles, I will describe the same more fully, referring to the accompanying drawing, in which—

Figure 1 is a top plan view of the apparatus employed in my improved coating of metal articles. Fig. 2 is an end view of the same. Fig. 3 is a cross section of the same on the line 3—3 Fig. 1. Fig. 4 is a longitudinal section of the same on the line 4—4 Fig. 1, looking in the direction of the arrow. Figs. 5 and 6 are views of the swabbing devices employed. Fig. 7 shows another form of the device.

Like symbols of reference herein indicate like parts in each of the figures of the drawing.

As illustrated in the drawing, 1 represents the tank, which is provided with the usual heating furnace 1' under the same for heating the materials within such tank for the coating of the articles to the desired degree, and such tank is provided with the lower or base portion 2 and the upper portion 3 extending up from and at one side of said lower portion. Within the lower portion 2 of the tank 1 and extending longitudinally of the same and centrally thereof is a wall 4, which extends down from the top of said portion for a suitable distance and divides such portion into the compartments 5 and 6, as well as forming part of the inner wall of the upper portion 3 located above the compartment 5. The wall 4 is provided with the projecting portions 7 and 8 at each end of the same, which extend from each side of said wall, and are adapted to form pockets 9 and 10 in said wall and on each side of the same for the purpose hereinafter described. Within the tank 1 are the two shafts 11 and 12, one of which is placed on each side of such tank and preferably on an incline in parallel lines with each other. 75 These shafts 11 and 12 are power driven in any suitable manner and are adapted to be rotated or revolved in the same and in the proper direction, as shown by the arrows in Fig. 3. The shaft 11 is provided with a wheel 13 having radial arms 14 thereon at each end of the same, and the shaft 12 is provided with a similar wheel 15 having similar arms 16 thereon at each end of the same. These wheels 13 and 15 are also arranged so that the ends of their respective arms 14 and 16 will travel within their respective pockets 9 and 10 in the wall 4 of the tank 1 in the movement of said wheels through said tank by the shafts 11 and 12, 80 and are also arranged so that such arms on the end wheels 13 and 15 will overlap and at the same time be away from each other by their being in the pockets 9 and 10 of the wall 4. When such arms 14 and 16 on the 85 wheels 13 and 15 are in movement through the tank 1, the lower ends of the same will pass along and be adjacent to the curved

guides or bottoms 17 and 18 in the compartments 5 and 6 respectively of said tank, and such bottoms are connected together at their inner ends by the central raised portion 19 5 between the same.

The use and operation of my improved apparatus for coating metal articles is as follows: The pipes or tubes *a* are thoroughly cleaned on their interior and exterior surfaces in the usual or in any suitable manner to remove all scale, silicates and oxids therefrom, and the compartments 5 and 6 of the portion 2 in the tank 1 are filled with the coating compound, such as lead and 10 tin, or zinc, which forms the coating bath *b*, and reaches the level of the wall 4, or slightly above the same, while the flux bath *c* of the usual material or compound for preparing the pipes or tubes *a* for the coating compound in the bath *b* is placed in the upper portion 3 of the tank and rests upon that part of the material of the coating bath *b* that is within the compartment 5 of said tank. The tank 1 being thus ready for the 15 coating operation, the pipes *a* so cleaned are each placed between two of the alined arms 14 on the wheels 13, as said wheels are revolved by the shaft 11, and such pipes are thus passed down through the flux bath *c* 20 in the portion 3 of the said tank, and then they are passed by said wheels into the coating bath *b* in the compartment 5 of the lower portion 2 of said tank. When each of the pipes *a* carried by the arms 14 on the 25 wheels 13 reach the raised portion 19 on the guides or bottoms 17 and 18 of the tank 1 they pass over said raised portion and are each caught by and between two of the alined arms 16 on the wheels 15, which 30 wheels are being revolved in the same direction as the wheels 13, so that such arms will act to carry said pipes through the coating bath *b* in the compartment 6 of the lower portion 2 of said tank until they reach the 35 upper part of said compartment and then each of said pipes are ejected from said compartment and out of said tank on the supporting table 20 at the side of said tank. As each one of the pipes *a* are thus passed 40 through the flux bath *c* and coating bath *b* and are ejected from the tank 1, any surplus material from said bath *b* is drained from said pipes back into said bath by reason of one end of such pipes being slightly elevated 45 on account of the wheels 13 and 15 at one end of the tank 1 being so elevated and the coating compound entering said pipes in their passing from the bath *c* into the bath *b* being heavier than the flux will 50 hold said flux at its level, so that it is kept in the flux bath *c* and does not thereby mix with said coating. When the pipes *a* are thrown out of the tank 1 after being so coated in the bath *b* and onto the asbestos 55 60

coated table 20, each of the same can then be 65 caught by any suitable means or mechanism and passed through a suitable swabbing device 21, which is composed of a resilient collar or piston 22 of asbestos or other suitable material supported on a rod 23 and engaging 70 with the interior of such pipe and a die 24 having a base 25 and movable cover 26 provided with similar material 27 for engaging with the exterior of such pipe to recover any further surplusage of the coating 75 material upon such surfaces of said pipe, and to further coat any places on said pipe which may not have taken the molten coating while passing through said tank.

It will be evident that the swabbing operation 80 on both the interior and exterior surfaces of the pipes can be performed at one time as described, or at separate times, and by a continuous operation, as desired, while other articles than pipes can be coated such 85 as rods and bars, and sprocket and chain devices used in conveying the articles through the tank by a rotary movement instead of the rotating wheels, as shown in Fig. 7, by sprocket-wheels 13' and 15', chain 14' and 90 arms 16' on said chain.

Various other modifications and changes 95 in the apparatus employed in my improved coating of metal articles may be resorted to, without departing from the spirit of the invention, or sacrificing any of its advantages.

It will thus be seen that in my improved coating of metal articles, such as pipes, the pipes in striking the coating compound in the first compartment at the bottom of the 100 tank will drive the flux previously placed on such pipes ahead of the coating compound, which will permit such flux to remain above said compound in its bath, and then such pipes are passed under the partition or wall into the second compartment and are raised out of the molten mixture or coating compound for the swabbing operation, all by mechanical means, thereby enabling the rapid handling and coating of 105 such pipes. With one end of the pipes being slightly elevated in passing through the tank, so as to incline such pipes, the material or ingredients composing the flux bath and coating bath to which such pipes are 110 subjected will always remain, or go back into their respective baths in the tank and thereby prevent any waste of such material, as well as some of the material of the coating bath removed by the swabbing process can 115 be saved into suitable pots or in any suitable devices, so that such pipe will receive a uniform and thin coating at the least possible expense. The apparatus employed being automatic in its operation will not require any attention or handling of the pipes 120 and will perform its work in a clean and workmanlike manner.

What I claim as my invention and desire to secure by Letters Patent is—

1. In an apparatus for coating metal articles, the combination with a tank having a bath of molten coating material therein and a bath of flux above and at one side of said coating bath and contacting therewith, and means within said tank having overlapping arms for carrying and passing the articles through said flux and coating baths.

2. In an apparatus for coating metal articles, the combination with a tank having a bath of molten coating material therein and a bath of flux above and at one side of said coating bath and contacting therewith, and rotary means within said tank having overlapping arms for carrying and passing the articles through said flux and coating baths.

3. In an apparatus for coating metal articles, the combination with a tank having a bath of molten coating material therein and a bath of flux above and at one side of said coating bath and contacting therewith, and rotary means on each side of said tank and adapted to overlap each other for carrying and passing the articles through said flux and coating baths.

4. In an apparatus for coating metal articles, the combination with a tank having a bath of molten coating material therein and a bath of flux above and at one side of said coating bath and contacting therewith, and rotary means on each side of said tank having radial arms thereon and adapted to overlap each other for carrying and passing the articles through said flux and coating baths.

5. In an apparatus for coating metal articles, the combination with a tank having a bath of molten coating material therein and a bath of flux above and at one side of said coating bath and contacting therewith, said tank having a curved bottom guide, and rotary means on each side of said tank having arms adapted to overlap each other for carrying and passing the articles through said flux and coating baths and along said bottom guide.

6. In an apparatus for coating metal articles, the combination with a tank having a bath of molten coating material therein and a bath of flux above and at one side of said coating bath and contacting therewith, said tank having a doubled curved bottom guide provided with a raised central portion between the same, and rotary means on each side of said tank having arms adapted to overlap each other for carrying and passing the articles through said flux and coating baths, along said bottom guides and over said raised portion.

7. In an apparatus for coating metal articles, the combination with a tank having a

bath of molten coating material therein and a bath of flux above and at one side of said coating bath and contacting therewith, a division wall in said tank for dividing said coating bath into two compartments, and means within said tank and on each side of said wall for carrying and passing the articles through said flux bath and each of said coating compartment baths.

8. In an apparatus for coating metal articles, the combination with a tank having a bath of molten coating material therein and a bath of flux above and at one side of said coating bath and contacting therewith, a division wall in said tank for dividing said coating bath into two compartments, and rotary means within said tank and on each side of said wall for carrying and passing the articles through said flux bath and each of said coating compartment baths.

9. In an apparatus for coating metal articles, the combination with a tank having a bath of molten coating material therein and a bath of flux above and at one side of said coating bath and contacting therewith, a division wall in said tank for dividing said coating bath into two compartments, and rotary means within said tank and on each side of said wall for carrying and passing said articles through said flux bath and each of said coating compartment baths.

10. In an apparatus for coating metal articles, the combination with a tank having a bath of molten coating material therein and a bath of flux above and at one side of said coating bath and contacting therewith, a division wall in said tank for dividing said coating bath into two compartments and provided with pockets on each side of the same, and rotary means within said tank and on each side of said wall and adapted to overlap each other in said pockets for carrying and passing the articles through said flux bath and each of said coating compartment baths.

11. In an apparatus for coating metal articles, the combination with a tank having a bath of molten coating material therein and a bath of flux above and at one side of said coating bath and contacting therewith, a division wall in said tank for dividing said coating bath into two compartments and provided with pockets on each side of the same, said tank having a curved bottom guide in each of said compartments, and rotary means within said tank on each side of said wall and adapted to overlap each other in said pockets for carrying and passing the articles through said flux bath and along said guides in each of said coating compartment baths.

12. In an apparatus for coating metal articles, the combination with a tank having a bath of molten coating material therein and

4
a bath of flux above and at one side of said coating bath and contacting therewith, a division wall in said tank for dividing said coating bath into two compartments and 5 provided with pockets on each side of the same, said tank having a curved bottom guide in each of said compartments with a raised central portion between the same, and rotary means within said tank on each side 10 of said wall and adapted to overlap each other in said pockets for carrying and pass-

ing the articles through said flux bath and along said guides in each of said coating compartment baths and over said raised portion. 15

In testimony whereof, I, the said ULYSSES S. ARMSTRONG, have hereunto set my hand.

ULYSSES S. ARMSTRONG.
